UNITED STATES PATENT OFFICE.

CHARLES EDWARD HAVILAND, OF LIMOGES, FRANCE.

DESIGN FOR A PLATE.

SPECIFICATION forming part of Design No. 33,072, dated August 14, 1900.

Application filed May 31, 1900. Serial No. 18,679. Term of patent 7 years.

To all whom it may concern:

Be it known that I, CHARLES EDWARD HAVILAND, a citizen of the United States, residing at Limoges, in the Republic of France, have invented and produced a new and original Design for a Plate or Similar Article, of which the following is a specification, reference being had to the accompanying drawings, forming a part thereof, and in which—

Figure 1 is a top view of a plate bearing and incorporating my design, and Fig. 2 a vertical section through a portion of same.

The leading feature of my design consists in the new and original ornamental form and configuration of the plate or similar article, substantially as shown in the drawings.

In the drawings, A designates the plate, and B the rim thereof, which rim has the scal-

loped outer edge C and bears upon its upper surface, adjacent to the said outer edge, the ornate scalloped configuration D, the latter extending entirely around said rim and following, substantially, the line of the scallops of the said edge C. The scalloped configuration D is slightly in relief and is of the character illustrated.

What I claim is—

The design for a plate or similar article, substantially as shown and described.

Signed at Paris, in the Republic of France, this 17th day of May, A. D. 1900.

CHARLES EDWARD HAVILAND.
